TOOL INSTALLED CONNECTOR AND PROCESS FOR ITS INSTALLATION

Julian Rogoff, New York, N. Y., assignor to Burn-
dy Engineering Company, Inc., a corporation
of New York

Application March 19, 1941, Serial No. 384,079

2 Claims. (Cl. 173—269)

My invention relates to low cost wire terminals and similar connectors, suitable for installation by means of a properly designed tool.

A main object of my invention is to provide a very inexpensive wire terminal which is comparable in cost with a solder terminal but which can be installed without the use of solder.

Another object of my invention is to make it possible to manufacture my connector from sheet metal on high speed, automatic machinery.

Still another object is to provide a connector that can be installed by means of a simple hand-operated tool.

Another object of my invention is to provide a connector which will accommodate any one of a range of wire sizes, without change of any of the parts and which can be assembled to any one of the wires by means of the same tool.

Another object of my invention is to provide a connector which has excellent electrical conductivity and a good mechanical grip.

I accomplish these and other objects and obtain new results as will be apparent from the devices described in the following description, particularly pointed out in the attached claims, and illustrated in the accompanying drawings in which,

Fig. 1 shows a perspective view of a terminal according to my invention in the original condition, i. e., before appliance of the tool shown in Fig. 20.

Fig. 2 shows a longitudinal sectional view of the embodiment shown in Fig. 1, in final condition, together with the end of a cable gripped by the connector, said section taken along the line 2—2 in Fig. 3.

Fig. 3 shows a cross-section taken along the line 3—3 in Fig. 2.

Fig. 4 shows a perspective view of another embodiment of my connector, in original condition.

Fig. 5 shows a sectional view of the embodiment shown in Fig. 4 in final condition taken along the line 5—5 in Fig. 6.

Fig. 6 shows a cross-section taken along the line 6—6 in Fig. 5.

Fig. 7 shows a perspective view of another embodiment of my connector in original condition.

Fig. 8 shows a sectional view of the embodiment shown in Fig. 7 in final condition and taken along the line 8—8 in Fig. 9.

Fig. 9 shows a cross-section taken along the line 9—9 in Fig. 8.

Fig. 10 shows a perspective view of another embodiment of my connector in original condition.

Fig. 11 shows a sectional view of the embodi-

ment shown in Fig. 10 in final condition and taken along the line 11—11 in Fig. 12.

Fig. 12 shows a cross-section taken along the line 12—12 in Fig. 11.

Fig. 13 shows a perspective view of still another embodiment of my connector in original condition.

Fig. 14 shows a sectional view of the embodiment shown in Fig. 13 in final condition and taken along the line 14—14 in Fig. 15.

Fig. 15 shows a cross-section taken along the line 15—15 in Fig. 14.

Fig. 16 shows still another embodiment of my connector seen from above.

Figs. 17, 18 and 19 show three subsequent steps 15 of the indenting operation used in bringing my connector into final shape.

Fig. 20 shows the working head of a tool used in said operation.

Referring particularly to the embodiment of my invention shown in Figs. 1, 2 and 3, numeral 10 indicates the connector with a lug body 11 ending in the terminal plate 12 and connected to a U-shaped body section 13. In the final condition, the ends 13a and 13b of the U are bent about 25 the conductor 14, forming a socket. The wall of said socket is impressed by application of a pressing tool whereby the socket is indented into the conductor 14. An upper impression 15a interlocks the overlapping ends 13a and 13b of the U. Said impression runs in longitudinal direction, that is to say, its main dimension is parallel to the central axis of the conductor 14. This impression does not, however, extend as far as the front and back ends of the U, leaving unimpressed margins 35 16a and 16b at both sides. Thereby the side openings of the socket are not distorted and provide for a gradual compression of the conductor 14, eliminating any tendency to shear strands of the conductor. The lower portion of the socket is, preferably, similarly impressed by a longitudinal impression 15b to insure maximum mechanical grip and electric contact. This impression is located diametrically opposite to said first impression.

45 Referring particularly to the modification shown in Figs. 4, 5 and 6, the connector 20 consists of the lug body 21 and the slotted body 27, having two longitudinal slots 28. The lug body 21 ends in the terminal plate 22 and has a U-shaped section 23. In the final condition the legs 50 23a and 23b of the U pass through the slots 28 and, beyond said slots, the ends of said legs are bent whereby the bodies 21 and 27 together form a socket about the conductor 24. Indenting impressions 25a and 25b correspond to similar im-

pressions in the embodiment shown in Figs. 1 to 3. The lug body 21 has bent portions 29a and 29b whereby a channel running in a direction crossing the longitudinal direction is formed. This channel shape of the lug body increases the strength of the body at that portion where it is most needed, that is where the conductor is crimped. In addition, this shape helps to guide the conductor into the proper position in the clamping element, and the bend 29b adjacent to the terminal tongue 22 raises the conductor contacting section of the body so that there is sufficient clearance between the projecting end of the cable 14 and the terminal plate 22.

Referring particularly to the embodiment shown in Figs. 7, 8 and 9, the connector 30 is a body comprising the lug section 31 ending in the terminal plate 32, the U-shaped section 33 with legs 33a and 33b, and the slotted section 37 with two longitudinal slots 38. A section 31a connecting sections 33 and 37 is provided with a hole 37b for the passage of the conductor 34. In the final condition, section 31a is bent upward and section 37 bent to the right side into horizontal position. Then the U-legs 33a and 33b pass through the slots 28 forming a socket similarly as the corresponding parts in Figs. 5 and 6. Indenting impressions 35a and 35b are provided as in the precedent modifications.

Referring particularly to the modification shown in Figs. 10, 11 and 12, the connector 40 comprises a U-shaped section 43, an intermediate section 47a, a slotted section 47 and a terminal plate 42. In the final condition the section 47a is bent upward so that the hole 47b provided in this section serves as a passage for the insertion of the cable 44. The U-shaped section 43 is bent to the right side so that the legs 43a and 43b pass through the slots 48 provided in the section 47. Indenting impressions 45a and 45b are provided as in the precedent modifications.

The modification 50 shown in Figs. 13, 14 and 15 is similar to that shown in Figs. 4 to 6, but differs in that the lug body 51 has the longitudinal slots 58 and the upper body 53 is U-shaped. In the final condition the ends 53a and 53b of the U passing through the slots 58 are bent below the slots. Here the channel-shape formed by bends 59a and 59b, in addition to the advantages previously mentioned, provides a recess for the bent ends 53a and 53b and thereby a flat position of the connector and the terminal plate 52.

The modification shown in Fig. 16 is similar to that shown in Figs. 13 to 15, but differs in that the lug body 61 has an additional section 67 extending to the side opposite to the terminal plate 62 in longitudinal direction. Body section 67 has two lateral wings, the original position of which is illustrated by dotted lines as at 67a. In the final condition the wings are clamped about the conductor 64 as at 67 whereby section 67 provides for additional grip and support of the conductor.

All these modifications show longitudinal impressions in the socket wall indenting into the conductor and leaving unindented margins at the front and at the back side of the socket. In addition to or instead of these impressions and indentations, there may be one or more similar impressions indenting into the conductor at any other portion of the socket wall. In addition to the indentations, the inner surface of the socket contacting the conductor may be serrated for better grip. The lug body may be made from sheet metal, preferably of uniform thickness.

The inner distance of the longitudinal slots is approximately equal to the diameter of the largest conductor which the clamping element shall accommodate. The U-legs are of such dimensions and so spaced that they fit into the slots. The ends of the U-legs may be slightly staked after insertion into the slots to prevent them from dropping out in handling or transportation. Such staking, however, is done in a manner that does not interfere with the free sliding of the legs in the slots.

The clamping element is preferably installed in the following way: First the conductor is inserted between the U-legs. Then the clamping element is crimped around the conductor whereby a closed tubular socket is formed. Then the wall of the socket is impressed for indentation into the conductor. In the case of the slotted embodiment, the ends of the U-legs passing beyond the slots may be finally interlocked by applying a flattening pressure to them in the direction toward the slotted body.

My clamping element is adapted for quick, easy and inexpensive installation. According to my further invention, such installation may be achieved by using a single tool completing all necessary steps in immediate sequence by one operation of the tool.

An embodiment of an installation tool suitable for this purpose is shown in Fig. 20. The tool 70 may be pliers-like or of similar character and may have a pair of jaws 71 and 72 shaped according to the special modification of the clamping element to be installed. In the shown example, one jaw 71 of the tool 70 is made with a longitudinal punch 71a with a slight taper 73 along its width. This taper is so designed that, upon closing of the tool, the jaw 71 will spread the ends of the U-legs, thereby binding the U-shaped body to the slotted body. The other jaw 72 of the tool 70 has a longitudinal groove 72a with a round wall to accommodate the head bend of the U.

Fig. 17 shows the connector 84 contacting parts of the jaws 71 and 72 at a larger scale together with a slotted embodiment 80 of the clamping element in cross-section. The jaw 71 has already begun to spread the ends of the U-legs while the jaw 72 has already begun to impress and to indent the head bend of the U.

Upon further closing of the tool, the punch 71a presses into the wall of the socket and indents said wall into the conductor. At the same time, the grooved portion of the jaw 72 presses the U-head and indents it deeper into the conductor. Fig. 18 shows the details of Fig. 17 during this further step of the operation. Here the ends of the U-legs are more bent to the side.

Further closing of the tool causes still deeper indentations and pressing of the ends of the U-legs against the slotted body section. In the final condition shown in Fig. 19, these ends are depressed by the jaw 71 from the shape shown by dotted lines 74 to a somewhat flattened shape whereby the said ends are interlocked and a tight permanent assembly is formed.

Both the round groove 72a and the punch 71a are made slightly less long than the width of the U in direction of the conductor in order to avoid distortion of the opening edges of the socket and of shearing effect on the conductor. In addition, the shorter length of the punch jaw 71 provides for final impression of the U-leg ends flattening the central parts of said ends and thereby forcing some of the material from said

central parts to the outer parts of said ends whereby said outer parts are made somewhat thicker and said ends are additionally secured against return through the slots. This shape of the U-leg ends is to be seen best from Fig. 14 at 53a and 53b.

My clamping element can be used for a range of conductor sizes because the socket is formed according to the actual size of the conductor. For example, in the slotted embodiments the U-legs will slide through the slots until the U-head contacts the conductor. As the U-legs slide through the slots, they are gradually spread by the taper 73 of the punch 71.

I desire it understood that my invention is not confined to the particular forms or uses shown and described, the same being merely illustrative, and that the invention may be carried out in other ways without departing from the spirit of my invention and, therefore, I claim broadly the right to use all equivalent instrumentalities and processes coming within the scope of the appended claims, and by means of which, objects of my invention are attained and new results ac-

complished, as it is obvious that the particular embodiments herein shown and described are only some of the many that can be employed to attain these objects and to accomplish these results.

5 I claim:

1. A sheet metal connector attached to a metal cable, having a U-shaped body section formed into a cable receiving socket and made of malleable metal adapted to be cold worked under pressure; a metal plate made of malleable metal having two parallel slots therein through which the legs of the U-shaped body section extend; said legs bent over to lock the cable receiving socket and the plate in contact with the metal cable; the metal cable and connector locked to each other by an indentation by which the metal of the connector is cold worked into the metal of the cable.
2. A connector according to claim 1, characterized by having the U-shaped body section and metal plate formed out of a single sheet of metal, having an aperture between the plate and section to permit the entrance of the cable.

JULIAN ROGOFF.
